CLAIM

The ornamental design for a solar powered lamp, as shown and described.

DESCRIPTION

FIG. 1 is a perspective view from above of a solar powered lamp showing my new design;

FIG. 2 is a perspective view of the lamp from below;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and

FIG. 9 is a perspective view of the lamp, anchored onto a post, with a first attachment atop; and,

FIG. 10 is a perspective and front view of the lamp, anchored onto an extendable post, with its solar unit in a detached manner, and with a second attachment atop.

The broken lines illustrate portions of the solar powered lamp that form no part of the claimed design.

1 Claim, 9 Drawing Sheets
